CALCULATING MACHINE

Hans Krebs, Berlin-Schöneberg, and Karl Westinger and
Ernst Altenburger, Oberndorf (Neckar), Germany, as-
signors to Olympia Werke A.G., Wilhelmshaven,
Germany

Filed May 4, 1960, Ser. No. 60,453

Term of patent 14 years

(Cl. D64—11)

FIG. 2

FIG. 1

FIG. 3

FIG. 4

FIG. 5

FIG. 1 is a front view of a calculating machine showing our new design;

FIG. 2 is a perspective view thereof;

FIG. 3 is a side view, the side opposite thereto being similar in appearance;

FIG. 4 is a top view; and

FIG. 5 is a rear view thereof.

The essential features of our design reside in the portions shown in solid lines on the drawing.

We claim:

The ornamental design for a calculating machine, as shown and described.
